UNITED STATES PATENT OFFICE

2,039,593

HEAT TRANSFER COIL

Theodore N. Hubbuch and William G. O'Toole,
Louisville, Ky.

Application June 20, 1935, Serial No. 27,589

1 Claim. (Cl. 257—256)

This invention relates to heat exchangers and has special reference to a cooler for cooling fluids such as beer, ale and the like, the invention being preferably termed a beer cooler although, as will 5 presently appear, it may be used for cooling or heating any fluid which may be caused to flow through the device.

One important object of the invention is to provide an improved and novel device of this character which can be manufactured in a simple and economical manner.

A second important object of the invention is to provide an improved and novel form of such cooler constructed of two like and complementary castings so that the two castings can be made from a single pattern.

A third important object of the invention is to provide a novel device of this character having improved means for permitting the heat to pass from the liquid in the interior of the device outwardly.

A fourth important object of the invention is to provide a novel device of this sort wherein the castings are reinforced by means which also act to aid in the heat transfer.

A fifth important object of the device is to provide a coil with a simple means of cleaning and inspecting.

With the above and other objects in view, the invention consists in general of certain novel details of construction of combinations of parts hereinafter fully described, illustrated in the accompanying drawings and specifically claimed.

In the accompanying drawing, like characters 35 of reference indicate like parts in the several views, and

Figure 1 is an inside face view of one of the plates used herein.

Figure 2 is an outside face view of the other 40 of said plates.

Figure 3 is a section through the assembled device on the line 3—3 of Figure 2.

Figure 4 is a similar section on the line 4—4 of Figure 2.

The cooler of this invention is formed from two plates of substantially the same character.

Each of these plates consists of a rectangular casting or stamping 10 having on one side central portion 11 spaced evenly from the peripheral portion 12 of the casting 10. In this central portion 11 is formed a groove consisting of straight parallel portions 13 and return bends 14 each connecting an end of one portion 13 with the corresponding end of the adjacent portion 13 so that the corresponding end of the adjacent portion 13 is continuous from end to end. The face

of the central portion 11, except for the groove, lies in a plane so that when the two plates are properly assembled the planes of these faces will coincide and the groove of one plate will register with the groove of the other plate to form a tube 5 continuous from one end to the other.

Between the central portion 11 and the peripheral portion 12 of each plate is a groove 15 for the reception of a gasket 16 which seals the periphery of the joint between the two plates so that liquid 10 passing through the tube formed by the grooves 13 and 14 cannot escape from the cooler.

It will be observed that the groove portion 13 at each end of each plate terminates the groove in a rectilinear manner. One of the plates has 15 on its outside at each end a tubular boss 17 which connects with the groove of the plate at a very obtuse angle and in these bosses are screwed nipples 18 for the inlet and outlet of the beer or other fluid to be cooled.

On the outer side of each plate there are formed alternate parallel grooves 19 and ribs 20, the ribs 20 being positioned over the straight portions of the interior grooves while the exterior grooves are positioned between adjacent straight 25 portions of the fluid. The ribs 20 thus overlie and strengthen the thin portions of the plates overlying the fluid conducting grooves and also act as fins for transfer of heat from within the cooler which is surrounded by ice or other refrigerant when in use. The grooves 19 act to increase the area chilled by the refrigerant and also to decrease the thickness of the metal 30 through which heat transfer occurs.

At the ends of each groove 19 is provided flat 35 portions 21 which increase the thickness of the metal and strengthen the plates at the bends 14.

Along the edges of each plate are provided bolt holes 22, the holes in one plate being in alignment with the holes in the other plate when the two are 40 assembled in proper relation. Through the aligned openings pass bolts 23 provided with wing nuts 24 so that the two plates may be held tightly together or taken apart for cleansing by a simple manipulation without necessitating the use of 45 tools.

It is to be observed that the very obtuse angles at which the bosses and nipples lie in relation to the ends of the groove parts 13 enable fluid to flow into and out of the cooler without eddies and 50 thus without stirring up such fluids as beer and ale, such stirring being undesirable in certain types of liquids.

In use the two plates are assembled and one nipple is connected by a suitable tube to the 55

supply from the barrel or other vessel while the other nipple is similarly connected to the tap for drawing the beer or other fluid. Suitable refrigerant such as crushed ice is now packed closely around the cooler and the device is ready for use.

It is obvious that the two plates may be cast from the same pattern, it being merely necessary to make the boss parts detachable as is common in constructing patterns for castings having 10 projections one of which does not exist on the other. Similar arrangements may be made in the case of stampings.

There has thus been provided a simple and efficient device of the kind and for the purpose 15 specified.

It is obvious that changes may be made in the form and construction of the invention without departing from the principles of the invention. It is not, therefore, desired to confine the 20 invention to the exact form herein described but it is desired to include all such as come within the scope of the appended claim.

What is claimed is:

25 A cooler of the class described including a pair

of complementary cast plates of like form, each of said plates having a groove in one face formed of straight parallel portions connected at their ends by return bends, said grooves registering with each other to form a tube and provided with 5 inlet and outlet openings at the opposite ends of said tube, the faces in which the grooves are formed being plane surfaces to fit tightly together, the remaining faces of said plates being provided with ribs extending in alignment with the grooves, said last faces having grooves extending longitudinally between the ribs and depressed below the peripheral portions of the said last faces to provide thin walls for the straight 10 portions of the tube, said peripheral portions having complementary semi-circular grooves surrounding the first mentioned grooved portions, an elastic gasket held in said semi-circular grooves and sealing the joint between said plates, bolts passing through the peripheral portions between 15 the gasket and the edges of the plates, and wing nuts on said bolts to force the plates together and compress the gasket.

THEODORE N. HUBBACH.
